WARP BEAM AND METHOD OF MAKING

Oscar V. Payne, Leicester, Mass., assignor to
Crompton & Knowles Loom Works, Worcester,
Mass., a corporation of Massachusetts

Application December 24, 1935, Serial No. 56,041

5 Claims. (Cl. 242—124)

This invention relates to improvements in warp beams for looms and it is the general object of the invention to provide a strong durable beam which is of comparatively light weight because of its simple construction.

Warp beams ordinarily comprise a barrel having sliding warp heads movable to vary the width of the warp space. It is an important object of my present invention to form a warp head with two disks one of which is perpendicular to the axis of the beam and the other of which is dished or conical, the two disks being secured together by a spacing sleeve and tapering toward each other from the barrel toward the outer rim. The sleeve prevents crushing of the flat disk by pressure of the warp and the conical disk reinforces and strengthens the head because of its shape.

In order to have some form of support for the barrel while it is being wound and when in the loom, it has been common practice to provide a relatively long cylindrical plug fitted into the end of the barrel and having a bearing stem extending outwardly from the barrel. I have found that such a construction is not only heavy but unnecessary, and it is a further object of my invention to provide the gudgeon stem with a thin integral flange welded to the interior of the barrel, the flange being reinforced with radial webs if desired.

It is a further object of my invention to provide an improved clamp to hold the head in adjusted position, preferably by means which permit fastening of the clamp to the beam in a way to allow slight radial adjustment, together with means to cause the clamp to grip the barrel. The two fastening means for the clamp can be tightened in desired order, the clamp being preferably centered on the barrel and then fastened to the dished or conical disk.

Another object of my invention is the provision of blocks welded on the dished plate to receive the clamp screws and located so as to place the aforesaid sleeve preparatory to welding thereof to either disc.

It is still another object of my invention to form the barrel with a square end so that it will receive either a friction head bolted directly to the gudgeon flange, or the type of let-off shown in my prior Patent No. 1,803,143. In this way the beam, when in the loom, can be used with two different types of let-off.

It is a still further object of my invention to provide an improved method for assembling the warp head, the method involving the steps of securing the clamp bolt retaining blocks to the

conical disk to serve as guide means for the sleeve so that the latter can be spaced from the warp surface of the barrel and secured to the conical disk while being so located. The method thereafter contemplates welding or otherwise securing the sleeve to the flat disk along an area between the barrel and sleeve with subsequent rolling or pressing the edges of the flat disk around the rim of the conical disk.

With these and other objects in view which will appear as the description proceeds, my invention resides in the combination and arrangement of parts set forth hereinafter.

In the accompanying drawings wherein a convenient embodiment of my invention is set forth,

Fig. 1 is an elevation of one end of the beam, partly in section, showing the preferred form of clamp,

Fig. 2 is a transverse section on a reduced scale, on line 2—2, Fig. 1, parts being omitted,

Fig. 3 is an end elevation in the direction of arrow 3, Fig. 1, the gudgeon being in section,

Fig. 4 is a detail section on line 4—4 of Fig. 2,

Figs. 5, 6 and 7 show successive steps in the method of making the warp head,

Fig. 8 is a detail section on line 8—8, Fig. 2, on an enlarged scale,

Fig. 9 is a fragmentary plan view of the beam and beam head having a modified form of clamp,

Fig. 10 is an end elevation of the clamp taken in the direction of arrow 10, Fig. 9.

Referring to the drawings, the beam barrel 10 is made preferably of pipe and has its outer surface ground to present a smooth uniform surface to the warp threads. Since both ends of the beam are alike but one end will be described. A supporting gudgeon 11, as shown in Fig. 1, comprises a stem 12 turned to be true and receivable by a bearing either in the winding machine or the loom. A thin flange 13 integral with the stem has its periphery turned on the gudgeon centers to fit the internal diameter of the pipe. By means of a jig not shown the gudgeon axis is aligned with the pipe axis, and in this position the flange is welded to the interior surface of the barrel pipe. A beveled edge on the flange, indicated at 14 in Fig. 1, provides room for the welding metal. In this way the gudgeon is firmly secured to the end of the pipe with its axis true with that of the pipe. The latter may then be turned about the gudgeon axes and given a true smooth warp receiving surface of desired size. Reinforcing integral radiating webs 15 may project from the inner surface of the flange to

the inner end 16 of the gudgeon, as shown in Fig. 1, thereby stiffening the flange and preventing bending of the same should the outer end of the stem be subjected to a severe blow.

When the beam is to be used in a loom having an ordinary friction let-off, a friction head 23 with a cylindrical shell 24 will be provided. The shell will have a polished surface 22 and will be formed with a web 23 through which extends bolts 24. The bolts are tapped into the flange 13 so that the friction head is tightly secured to the barrel. The arrangement of the bolts and shape of the web 23 may be as shown in Fig. 3. The friction head is formed with a shoulder 19 which fits closely around the end of the barrel to center the head with the barrel axis. In this connection it will be noted that the flange 13 forms a square end for the barrel.

A radial driving rib 25 may be cast integral 20 with the web and cylindrical flange 21 to receive the torque of a winding machine. If a different type of let-off from that employing friction on the surface 22 is desired the bolts 24 can be removed to permit the application of such a type of 25 let-off as shown, for instance, in my prior Patent No. 1,803,143, the square end of the barrel facilitating the application.

The adjustable warp head 30 forming an important part of my invention comprises a flat 30 sheet metal disk 31 having its outer periphery rolled or pressed as at 32 to receive the rim 33 of a second disk 34 which may be dished or of general conical form. That part of the disk 34 adjacent the barrel may be flattened to present a planate portion 35 substantially perpendicular to the axis of the barrel. The rim 33 is caught tightly by the edge 32 either by pressure or by welding, as desired, and may also be flattened, as 40 shown in Fig. 1.

In order to reinforce the two disks a cylindrical sleeve 40 is interposed between the flange disk 31 and the flat part 35 of the conical disk, the sleeve having an internal diameter somewhat 45 greater than the external diameter of the barrel. A pair of blocks 41 and 42 are welded to the inner surface of the planate part 35 of the conical disk, and lie preferably against the sleeve. In this way the blocks locate the sleeve so that 50 it is held spaced from the outer warp surface of the pipe. The disks 31 and 34 have aligned barrel receiving bores 45 as shown in Fig. 1.

The method of assembling the warp head is shown in Figs. 5, 6 and 7. The blocks 41 and 55 42 are welded to the planate part 35 of the conical disk one on each side of the bore 45, as shown in Fig. 5, with their inner or adjacent faces 46 located equal distances from the axis of bore 45, the faces 46 being separated by a distance substantially equal to the outer diameter of the sleeve 40. The latter is then laid against the inner surface of flat part 35 between the blocks to be positioned by the latter, as seen in Fig. 6. The sleeve is then welded to the conical disk, as 60 at 43, along the outer surface of the sleeve. Flat disk 30 is then placed with its bore aligning with that of the other disk, the rims 32 partly rolled, as shown in Fig. 7. The sleeve is then welded to the flat disk, along an area lying between bore 65 45 and the sleeve, after which the rims are pressed tightly in place, as already described and shown in Fig. 1. The greater internal diameter of the sleeve provides room for this last weld, and also 70 keeps any roughness which might accompany 75

the weld from scratching the barrel as the warp head is adjusted.

The placing of the blocks is facilitated by an angular depression 47, one of the blocks lying against an edge of the depression during the block welding operation, as suggested in Fig. 8. The depression also has a use to be set forth hereinafter.

In order that the head 30 may assume different longitudinal positions along the barrel I provide a clamp designated generally at 50. This clamp has two heads 51 and 52 separated by a narrow slot 53 and connected by a bolt 54 threaded into head 52 and having a head 56 which shoulders against the head 51. By slackening the bolt the clamp is released from the barrel so that it may be turned to facilitate sliding along the length of the barrel. The bolt head 56 is adjacent the depression 47, the latter permitting swinging of a wrench without interference by the conical disk 34.

The clamp is held to the disk part 35 by a pair of screws 60. Each screw has a threaded shank 61 which extends through a hole 62 in the clamp of a somewhat larger diameter and is tapped into one of the blocks. A head 63 on each screw is received by a counter-bore 64 somewhat larger than the head. The reason for the difference in size between the screw and the hole 62 and counter-bore 64 is to permit slight relative movement of the clamp with respect to the axis of disk 34, thereby permitting the internal bore 65 of the clamp to fit closely against the warp barrel under slight tightening of bolt 54. When the screws 60 are tightened in place they hold the clamp frictionally against the outer surface of the flat part 35 to prevent any lost motion or play between the clamp and the warp head. Thereafter, bolt 54 is tightened and the clamp effectively holds the warp head to the beam 40 barrel.

In order to provide the barrel with a smooth surface the pipe of which it is constructed is ground or turned down to size. If for any reason the pipe should be twisted there is the likelihood that part of the barrel will be thin. In such a case a clamp such as that shown in Fig. 2 concentrates the pressure of the screw 54 at one point on the periphery of the barrel and I have found in occasional instances that a slight eccentricity of the barrel results. In order to distribute the pressure incidental to tightening the clamp over a larger area I employ the modified form shown in Figs. 9 and 10. The modified clamp 70 may be similar to the preferred form 55 in all respects except the manner in which the head is split. In this instance instead of having the slot 53 cut on a plane radiating from the axis of the barrel I dispose the slot diagonally as at 71 and provide a bolt 72 threaded into one of the clamp heads 73 and abutting the other clamp head 74 as at 75. I preferably make the slot 71 a rather steep inclination so that the overlapping parts 76 and 77 of the heads 74 and 73, respectively, will extend around an appreciable part of the barrel circumference. In this way the pressure is not concentrated as in the form shown in Fig. 2 but is distributed with the result that the eccentricity of the barrel due to the tight setting of the clamp is very materially reduced. 60 The modified form of clamp will be set in a manner similar to that described in connection with the preferred form and will differ from the latter 65 only in the direction of the slot 71.

From the foregoing it will be seen that I have 75

provided a warp head formed of two disks the outer rims of which are secured together by having one rolled over the other and the inner portions of which are held together by a sleeve secured to both disks and so located as to be out of engagement with the warp surface of the barrel, thereby permitting longitudinal adjustment without scratching the barrel.

It will also be seen that the gudgeon is formed with an integral flange which fits into the end of the barrel and is welded around its periphery to provide a strong bond. Also, it will be seen that the clamp is held to the conical or dished disk by screws which pass through holes in the clamp large enough to permit a slight relative movement of the clamp relatively to the disk, and that the clamp is further provided with a tightening bolt. The bolt can be used to effect a partial tightening of the clamp so that the latter has a close fitting contact with the barrel surface before the screws are tightened, the loose fit between the screws and the clamp permitting the latter to find its center around the barrel, after which the screws may be tightened to hold the clamp against the conical disk. The bolt is subsequently tightened to hold the clamp against the barrel without unequal strain which might otherwise arise but for the relative movement of the clamp with respect to the screws. Further, the blocks which receive the screws for the clamp serve also to position the sleeve which is secured to and reinforces the two disks forming the warp edge. Again, the flange of the gudgeon provides the beam barrel with a square end adapted for fitting either with the common let-off friction head or the positive let-off shown in my Patent No. 1,803,143. Lastly, it will be seen that the advantages growing out of the construction of the warp head are attained by following a method of construction wherein blocks are secured to the conical disk to position the sleeve, the latter being then welded to the conical disk, after which the flat disk is welded to the sleeve and then subjected to a rolling or pressing operation which will turn its rim over and around the rim of the conical disk.

It will further be seen that the modified form of clamp has its heads separated by a slot which extends diagonally with respect to the axis of the barrel, the purpose of this construction being to distribute the pressure of tightening the clamp over a comparatively large part of the circumference of the barrel. With a clamp formed as shown particularly in Figs. 9 and 10 the distortion of the shape of the barrel or its deviation from a true circle in cross section, is reduced to a minimum. While I have shown and described certain parts in connection with the friction head 20, these parts are not claimed herein but are reserved for a divisional application.

Having thus described my invention it will be seen that changes and modifications may be made therein by those skilled in the art without departing from the spirit and scope of the invention and I do not wish to be limited to the details herein disclosed, but what I claim is:

1. A warp beam head adjustable longitudinally along a hollow metallic barrel comprising a disk forming part of the warp head, blocks secured to the disk on opposite sides of the barrel axis

the and having surfaces adjacent the axis located at substantially equal distances from the latter, a reinforcing sleeve secured to the disk and positioned by said blocks, and a second disk for the warp head secured to the sleeve and also secured to the first disk, the internal diameter of the sleeve being greater than the external diameter of the barrel.

2. A warp beam head adjustable longitudinally along a hollow metallic barrel comprising a disk with a conical portion forming part of the warp beam head, blocks secured to the disk on opposite sides of the barrel axis, part of the conical portion of the disk being recessed to position one of the blocks, a clamp, means to secure the clamp to the blocks, and means accessible from a point adjacent the recessed part of the conical portion to tighten the clamp on the barrel.

3. A warp beam head adjustable longitudinally along a hollow metallic barrel comprising a warp thread engaging disk, a clamp secured to the disk and surrounding the barrel, a pair of heads on the clamp having substantially aligned axes which lie in a plane perpendicular to the axis of the barrel, said heads being separated by a slot oblique with respect to the head axes and lying in a plane transverse of the axis of the barrel, a portion of the circumferential periphery of the barrel being engaged by parts of both heads lying on opposite sides of said slot, and means extending through the heads to clamp the same on the barrel, said parts of the heads lying opposite the slot distributing the pressure of the clamp along said circumferential peripheral portion of the barrel.

4. A warp beam head adjustable longitudinally along a hollow metallic barrel comprising a warp thread engaging disk, a clamp secured to the disk and extending around the barrel, a pair of adjacent non-engaging heads formed on the clamp, a diagonal slot extending between adjacent portions of said heads lying in a plane transverse to the axis of the barrel and diagonal with respect to the plane of the clamp, those portions of the heads lying on opposite sides of the slot extending along and in contact with a substantial circumferential area of the barrel, and means to draw the heads together and force said clamp against the barrel, the pressure of the heads against the barrel being distributed over a continuous circumferential zone of the barrel extending from one head to the other.

5. A warp beam head adjustable longitudinally along a hollow metallic barrel comprising a warp thread engaging disk, a clamp secured to the disk, said clamp having an internal surface to engage a complete circumferential zone of the barrel, a pair of heads formed on the clamp separated by a diagonal slot extending obliquely with respect to the plane of the clamp and the axis of the barrel, the internal portions of the heads opposite the diagonal slot extending along and in engagement with the same zone of the surface of the barrel measured around the circumference of the latter, and means to draw the clamps together to force the clamp against the barrel, the disposition of the internal surfaces of the heads adjacent said slot distributing the pressure of the clamp along a circumferential area extending continuously from one head to the other.

OSCAR V. PAYNE.
